COMBINED TABLE AND SEAT UNIT

Alan H. Kempner, Jr., Purchase, N. Y.

Application May 29, 1957, Serial No. 46,400

Term of patent 14 years

(Cl. D33—14)

FIG. 1.

FIG. 2.

Figure 1 is a front perspective view with seats down of the combined table and seat unit embodying my new design, and

Fig. 2 is a rear perspective view with the seats up.

I claim:

The ornamental design for a combined table and seat unit, substantially as shown.
